UNITED STATES PATENT OFFICE.

ANTHONY D. MCLEAN AND CHARLES H. PICARD, OF SAN FRANCISCO,
CALIFORNIA.

HYDROCARBON-BURNER.

SPECIFICATION forming part of Letters Patent No. 723,010, dated March 17, 1903.

Application filed October 27, 1902. Serial No. 129,028. (No model.)

To all whom it may concern:

Be it known that we, ANTHONY D. MCLEAN and CHARLES H. PICARD, citizens of the United States, residing in the city and county 5 of San Francisco, State of California, have invented an Improvement in Hydrocarbon-Burners; and we hereby declare the following to be a full, clear, and exact description of the same.

10 Our invention relates to an apparatus for the combustion of oil or equivalent hydrocarbons.

It consists of a nozzle having openings for the admission of steam and oil and a peculiarly-shaped slotted plate through which the oil is delivered and a means for discharging the steam so as to impinge upon said plate and to be delivered in intimate contact and in essentially the same direction with the 20 sheet of oil which escapes through the plate.

It also comprises details of construction which will be more fully explained by reference to the accompanying drawings, in which—

25 Figure 1 is a transverse vertical section of our invention. Fig. 2 is a longitudinal vertical section of same. Fig. 3 is a transverse vertical section of a modification of our invention. Fig. 4 is a longitudinal vertical section of same. Fig. 5 is a top view of distributing-plate, Figs. 1 and 2. Fig. 6 is a top view of distributing-plate, Figs. 3 and 4.

The apparatus consists of a nozzle the body A of which has a central opening, as at 2, 35 through which the hydrocarbon liquid may be admitted. Upon one or both sides of this central opening passages 3 are made, and these are carried up to a point opposite the distributing-plate 4 and thence turned so that 40 the steam-jet is discharged against the flat face of this plate. The plate has its upper surface made in the form of a segment and has a slot made in it, as shown at 5. This slot communicates with the central oil-ad-

45 mission passage 2, so that the oil which is delivered under pressure will pass out in a sort of fan shape through the slot. The steam, striking against the side of the segment, is diverted outwardly through slots made either 50 between the segment and the similarly-shaped outer end of the nozzle, as shown at

6, or, if preferred, the periphery of the plate may be made wide enough to fill the space in the outer end of the nozzle A and have slots made through it. We have found, however, that by making this segmental portion sufficiently thinner than the width of the opening in the segmental part of A the channels 6 on each side of the channel 5 form a sufficient escape for the steam when the 60 steam is admitted upon either one or both sides of the distributing and disintegrating plate.

If preferred, the steam may be admitted through one of the passages 3 and the oil 65 through the other, in which case a single discharge-slot would suffice for each of the components, which are ultimately united to form the combustible. The action of the hot steam impinging against the distributing-plate 70 also serves to heat the oil and to assist in subdividing or comminuting it.

Having thus described our invention, what we claim, and desire to secure by Letters Patent, is—

75 1. The combination in a hydrocarbon-burner of a body portion having its outer end slotted in the direction of its length; said body having passages through it for the delivery of steam and oil; and a distributing-plate parallel with and seated in said slot so that its outer end is substantially flush with the outer end of said body, and against which plate the steam is directed laterally and caused to impinge and be diverted, said plate and the walls 80 of the slot forming separate discharge-passages for the steam and oil.

2. In an oil-burner the combination of a body portion having separate passages for steam and oil, and having its outer end slotted 90 inwardly; and a plate seated in said slot so that its outer end is substantially flush with the outer end of said body, said plate separating the oil and steam passages from each other and said plate and the walls of the slot 95 forming separate oil and steam discharges and said steam-passage adapted to direct the steam laterally against the plate whereby the steam is diverted and the oil-passage heated.

3. The combination in a hydrocarbon-burner 100 of a plate having a slotted segmental exterior periphery, a conducting pipe or holder hav-

ing a correspondingly-shaped outer end centrally slotted and forming a seat into which the plate is secured with its curved periphery essentially coincident with that of the holder, 5 a passage through which oil is delivered to the central slot in the plate, and a separate passage through which steam is delivered to impinge against the exterior of the plate and to be thence discharged and mixed with the 10 escaping hydrocarbon.

4. An oil-burner consisting of a conductor and head portion having a transverse segmentally-raised section at its outer end, and a slot or channel made transversely of said 15 section, a plate having a corresponding curvature at its outer periphery, said plate being fixed in the slot so as to separate the oil

and steam passages, and forming a separate slot or passage upon each side of it, an oil-conducting passage through which the hydrocarbon is delivered to the slot in the plate, and one or more independent passages through which steam is directed to impinge against the sides of the plate, to divert the steam and heat the oil-passage, and to be afterward discharged through the slots upon each side of the plate. 20 25

In witness whereof we have hereunto set our hands.

ANTHONY D. MCLEAN.
CHARLES H. PICARD.
